Primary Examiner — L. A. Grabenstetter

(57) **CLAIM**

The ornamental design for a case for mobile telephone, as shown and described.

DESCRIPTION

FIG. 1 is a front, left, and top perspective view of a case for mobile telephone, showing my new design;

FIG. 2 is a rear, right, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a second front, left, and top perspective view thereof, showing portions of the design in an alternate configuration; and,

FIG. 10 is a third front, left, and top perspective view thereof, showing portions of the design in a second alternate configuration.

The broken lines in the figures depict portions of the case for mobile telephone that form no part of the claimed design.

1 Claim, 10 Drawing Sheets
